Patented Mar. 14, 1922.

UNITED STATES PATENT OFFICE.

RALPH H. STEGEMAN, OF ANAHEIM, CALIFORNIA.

SUCKER-ROD TRAP.

1,409,424.

Specification of Letters Patent. Patented Mar. 14, 1922.

Application filed March 15, 1921. Serial No. 452,561.

To all whom it may concern:

Be it known that I, RALPH H. STEGEMAN, a citizen of the United States, residing at Anaheim, in the county of Orange and State 5 of California, have invented new and useful Improvements in Sucker-Rod Traps, of which the following is a specification.

It is the object of this invention to provide a device for automatically engaging and 10 holding a sucker rod with relation to a pump casing as the sucker rod is withdrawn section after section from the pump casing in order to permit of unscrewing and removal of the withdrawn sections.

15 More specifically the invention contemplates the provision of holding means readily secured to the pump casing with the sucker rod extending through the same, said holding means including a pivoted collar 20 normally swung by gravity into position engaging beneath one of the coupling members of the sucker rod, in order to prevent downward movement of the sucker rod, and also arranged to be swung upwardly to permit withdrawal of a section of the sucker 25 rod when a coupling member of the sucker rod impinges against the pivoted collar.

The invention also provides for the swinging of the pivoted collar entirely out of engagement with the sucker rod when so desired, means being provided for automatically yieldably retaining the pivoted collar in such position.

30 The invention will be readily understood from the following description of the accompanying drawings, in which—

Figure 1 is a side elevation of the device in position with relation to a pump casing and the sucker rod within the same.

40 Fig. 2 is a top plan view showing the holding means and sucker rod extended through the same.

Fig. 3 is a transverse section on the line 3—3 of Fig. 1.

45 Fig. 4 is a longitudinal section on the line 4—4 of Fig. 2 showing the pivoted collar of the holding means before the same is moved into engaging position with relation to the sucker rod.

50 Fig. 5 is a similar view showing the pivoted collar being swung upwardly by a coupling member of the sucker rod impinging against the same in order to permit of withdrawal of the sucker rod.

55 Fig. 6 is a fragmentary side elevation

showing the pivoted collar in its subsequent position engaging beneath the coupling member of the sucker rod to prevent return of the sucker rod into the pump casing.

Fig. 7 is a similar view showing the opposite side of the device.

Fig. 8 is a similar view showing the pivoted member swung all the way out of engagement with the sucker rod.

Fig. 9 is a detail section on the line 9—9 of Fig. 8.

The improved holding device is illustrated as employed in connection with a usual pump casing 1 having the sucker rod comprising sections 2 connected by enlarged 70 coupling members 3 extending through the pump casing.

The improved holding means is arranged to permit withdrawal of the sucker rod section after section, and to automatically 75 swing into engagement beneath each succeeding coupling member of the sucker rod to prevent subsequent return of the sucker rod into the pump casing while the withdrawn section of the rod is removed.

The holding member is preferably detachably mounted upon the upper end of the pump casing with the sucker rod extending through the same and having a pivoted collar counterbalanced at its upper end adapted to swing downwardly against the upper end of the holding member so as to engage a coupling member of the sucker rod, or to swing upwardly from the holding member so as to disengage the sucker rod.

In the particular embodiment of the invention illustrated, the holding member is shown as a casing 4 received over the end of the pump casing and having a bore provided with a lower end 5 receiving the pump casing, and an upwardly convergently tapering portion 6 forming a restricted opening 7 in the bore and then terminating in an outwardly tapering portion 8 at the upper end of the bore.

The casing 4 is preferably longitudinally split as shown at 10 and may be secured to the pump casing by means of set screws 11 extending radially through the casing 4 and engaging the pump casing. The restricted 105 opening 7 in the bore of casing 4 is of such size as to permit of the passage of the enlarged coupling members of the sucker rod, and the tapering portions 6 and 8 of the bore are arranged to guide the sucker rod into 110

axial alinement with the casing 4 as the sucker rod is moved either up or down with relation to the casing.

A collar plate 12 is pivoted to casing 4 so as to swing downwardly against the upper surface of the casing, said collar plate being provided with depending lugs 13 adapted to be received over opposite side surfaces of casing 4. A rod 14 is pivoted in casing 4 and in one of the lugs 13 and is provided with a squared portion 15 received through a co-operating squared opening 16 in the opposite lug of the collar plate. The rod may be held in position with relation to the collar plate and casing 4 by a usual nut 17 threaded onto its end beyond the squared portion 15 of the rod, and the opposite end of the rod terminates in an angularly disposed arm 18 having a counterbalancing weight 19 upon the end thereof and is preferably held in position by a nut 20 threaded onto the end of the arm. By this arrangement it will be seen that the collar plate is horizontally pivoted with relation to casing 4, and by reference to Fig. 1 it will be noted that the weighted arm 18 is so arranged as to normally swing the collar plate downwardly into position against the upper surface of casing 4.

The collar plate is provided with an opening 22 extending inwardly from its swinging end and terminating in a circular enlargement 23 having a wearing bushing 24 positioned around the rim thereof and arranged in alinement with the sucker rod extending through the holding device. This annular enlargement is of such diameter as to permit of the free passage therethrough of the sections of the sucker rod, while at the same time engaging the enlarged coupling members 3 of the sucker rod so as to prevent movement thereof through the collar plate.

In operation, as the sucker rod is withdrawn from the pump casing and through the holding device 10, the coupling members 3 will impinge against the under side of the collar plate 12, as shown in Fig. 4, so as to swing the collar plate upwardly into the position shown in Fig. 5 and thereby permit of withdrawal of the sucker rod. As soon as the coupling 3 has passed beyond the collar plate, it will be returned by weighted arm 18 to its position against the upper surface of casing 4, as clearly shown in Fig. 6, and will thus prevent return movement of the sucker rod into the pump casing by the impingement of coupling 3 against the wearing bushing of the collar plate. The projecting section of the sucker rod may then be unscrewed and removed in the usual manner. Succeeding sections of the sucker rod may then be withdrawn and removed in a similar manner.

When it is desired to make the holding device inoperative, the collar plate 12 is

swung upwardly and rearwardly upon its pivot a sufficient distance to entirely disengage the sucker rod, as clearly shown in Fig. 8, and the collar plate is preferably yieldably held in this position as by providing a recess 30 in the surface of one of the lugs 13 which is adjacent casing 4, and by providing a co-operating engaging member shown as a ball 31 in a bore 32 extending into casing 4, and containing a spring 33 yieldably urging the ball into contact with the adjacent surface of the lug 13 so as to engage in recess 30 and thereby retain the collar plate in its upwardly swung position. It will be understood that when sufficient force is exerted upon the collar plate, spring 33 will be compressed so as to permit disengagement of ball 31 from recess 30 in order that the collar plate may be swung back into operative position.

It will thus be seen that I have provided a simple and compact mechanism adapted to be readily mounted upon a pump casing and so arranged as to permit of the ready withdrawal of a sucker rod section after section, while also arranged to automatically swing into operative position beneath the succeeding coupling members of the sucker rod so as to prevent return of the sucker rod into the pump casing.

Various changes may be made without departing from the spirit of the invention as claimed.

What is claimed is:

1. The combination with a pump casing and a sucker rod therein having enlarged coupling members, of holding means secured to the pump casing with the sucker rod projecting through the same, and including a pivoted counterbalanced collar normally swung into position engaging beneath a coupling member of the sucker rod.

2. The combination with a pump casing and a sucker rod therein having enlarged coupling members, of holding means secured to the pump casing with the sucker rod projecting through the same, and including a pivoted counterbalanced collar normally swung into position engaging beneath a coupling member of the sucker rod, and arranged to be swung upwardly by the next lower coupling member upon the sucker rod impinging against the same so as to permit withdrawal of the sucker rod.

3. The combination with a pump casing and a sucker rod therein having enlarged coupling members, of holding means secured to the pump casing with the sucker rod projecting through the same, and including a pivoted collar having a weighted arm so as to be normally swung into position engaging beneath a coupling member of the sucker rod.

4. The combination with a pump casing and a sucker rod therein having enlarged

- coupling members, of holding means secured to the pump casing with the sucker rod projecting through the same, and including a pivoted collar normally swung into position 5 engaging beneath a coupling member of the sucker rod, said collar being also arranged to be swung out of engagement with said sucker rod and having yieldable engaging means for retaining the collar in said latter 10 position.
5. The combination with a pump casing and a sucker rod therein having enlarged coupling members, of holding means secured to the pump casing with the sucker rod projecting through the same, and including a pivoted collar normally swung into position 15 engaging beneath a coupling member of the sucker rod, and arranged to be swung upwardly by the next lower coupling member 20 upon the sucker rod impinging against the same so as to permit withdrawal of the sucker rod, said collar being also arranged
- to be swung upwardly beyond the position to which it is moved by said sucker rod and having yieldable engaging means for retaining the collar in said latter position. 25
6. The combination with a pump casing and a sucker rod therein having enlarged coupling members, of holding means having set screws for securing the same to the pump casing with the sucker rod projecting through the same, and including a pivoted counterbalanced collar normally swung into position 30 engaging beneath a coupling member of the sucker rod. 35
7. The combination with a sucker rod having enlarged coupling members, of holding means including a pivoted counterbalanced collar normally swung into position engaging beneath a coupling member of the sucker rod. 40

In testimony whereof I have signed my name to this specification.

RALPH H. STEGEMAN.
